United States Patent

Des. 240,371
Patented July 6, 1976

240,371

ATHLETIC SHOE

Bruce L. Shelly, Canton Ohio, and Michael L. Oliver,
Temperance, Mich., assignors to Point Four Limited,
Inc.

Filed Dec. 16, 1974, Ser. No. 530,971

Term of patent 14 years

Int. Cl. D2—04

U.S. Cl. D2—309

FIG. 1 -

FIG. 2 -

FIG. 3 -

FIG. 4 -

FIG. 6 -

FIG. 5 -

FIG. 1 is a top plan view of an athletic shoe showing our new design;

FIG. 2 is a right side elevational view thereof;

FIG. 3 is a front elevational view thereof;

FIG. 4 is a rear elevational view thereof;

FIG. 5 is a left side elevational view;

FIG. 6 is a bottom plan view thereof.

I claim:

The ornamental design for an athletic shoe, substantially as shown and described.
